UNITED STATES PATENT OFFICE.

MARTIN A. EISENHOUR, OF PLYMOUTH, INDIANA.

CULTIVATOR.

SPECIFICATION forming part of Letters Patent No. 364,583, dated June 7, 1887.

Application filed March 26, 1887. Serial No. 232,503. (No model.)

To all whom it may concern:

Be it known that I, MARTIN A. EISENHOUR, a citizen of the United States, residing at Plymouth, in the county of Marshall and State of Indiana, have invented certain new and useful Improvements in Cultivators; and I do hereby declare that the following is a full, clear, and exact description of the same, reference being had to the annexed drawings, making a part of this specification, and to the letters and figures of reference marked thereon.

Figure 1 of the drawings is a perspective view of a cultivator embodying my invention; Fig. 2, a detail view in perspective of the clip for holding the cultivator-tooth; Fig. 3, a similar view in section of the clip, the cultivator-tooth, and the tooth-bar, the bolts which connect the two sections of the clip together being shown in dotted lines; and Fig. 4 is a detail view showing the manner of connecting the braces to the tooth-bar.

The object of the present invention is to provide simple and practical means for attaching the tooth-bar to the beam of the cultivator-frame, and also in connecting the teeth to the bar, as will be hereinafter described and claimed.

In the accompanying drawings, A represents the usual cultivator-frame, to which is connected the tooth-bar B, which may be of any desirable length for carrying the required number of teeth. The bar B is so constructed as to be attachable to any form of common cultivator by means of the slots *a* in the bar, through which pass clamping-hooks C, screw-threaded at their shank end, as shown at *b*, to receive nuts *c*, a washer being interposed between the nut and bar, as shown at *d*, Fig. 4. The hooked end of the clamping-hook C extends around the lower end of the posts D, there being two posts connected to the bar, as above described, the upper ends of said posts being suitably connected to the beam of the cultivator-frame. Should the distance between the lower ends of the posts D vary, the clamping-hook C may be moved along the slot *a* in a direction to or from the ends of the bar B, to adapt them to the position of the post, so that the hooked ends will extend around the same.

If the slots *a* are not sufficiently long to at-

tain the purpose above described, the hooks may be moved to the extremities of the slot, as shown in Fig. 4, and afterward turned so that their hooked ends will be opposite to the position shown, thereby reaching the distance from one post to the other.

In order to bring the teeth on different vertical planes, the angle of the bar B can be changed by removing one of the clamps C and replacing it in a reversed position, so that one of the posts will be connected to the front side of the beam and the other post on the rear side thereof, thereby bringing the bar from a right angle to an acute angle with the line of draft.

If it is desired to use the bar for other than spring-teeth, the bolts that hold the clips, hereinafter described, may be removed and the shank of the bolt or hook inserted through the bolt-holes.

The clip, which is intended to hold the tooth firmly in its place to the bar B, (any form of spring-tooth,) consists of the two sections E F, the upper section, E, being in the form of a cap-plate, with holes *e* for the fastening-bolts to pass through, as shown in dotted lines, Fig. 3. The lower section, F, is preferably serrated upon its under side, to prevent it from slipping on the bar B, to which it is attached by the single bolt *f* and nut *g*, the latter passing through the bar, as shown in Fig. 3; and when the two sections of the clamp are together the tooth G is firmly held between them.

The center of the clip-section F is countersunk, as shown at *h*, for the reception of the head of the bolt *f*, as is also the ends of said section, as shown at *i*, for the reception of the heads of the bolts that connect the two clip-sections together.

The section F is sunken upon its upper side to receive the tooth and form a seat therefor, the outer edges of which are slightly convex, as shown at *k*. At each end of this sunken space are shoulders *l*, which are concave, as shown, and the cap-plate E is concavo-convex, so that it can be turned according to the form of tooth used, the concave or convex surface of the plate being brought in contact with the tooth, as the case may be, and also to adapt itself to the lower clip-section, F. A very simple and compact clip is provided that can be used with the usual forms of teeth employed

in cultivators; and when spike-teeth are used the bolts *f* are removed and the shanks of the teeth inserted in their place, as hereinbefore described.

5 Having now fully described my invention, what I claim as new, and desire to secure by Letters Patent, is—

1. In a cultivator, the combination, with the posts *D*, of the tooth-bar *B*, having slots *a*, 10 and the clamping-hooks *C*, for connecting the lower ends of the pests thereto, substantially as and for the purpose set forth.

2. The combination, with the teeth and tooth-

bar of a harrow, of a clip for holding the tooth thereto, consisting of a clip formed in two sections, *E F*, the former being concavo-convex, and the latter one of said sections having convex edges *k* and concave shoulders *l*, substantially as and for the purpose described.

In testimony that I claim the above I have 20 hereunto subscribed my name in the presence of two witnesses.

MARTIN A. EISEN HOUR.
